UNITED STATES PATENT OFFICE.

JULIUS A. PETZOLD, OF KANSAS CITY, MISSOURI, ASSIGNOR TO CHILDREN'S BED COVER FASTENER COMPANY, OF KANSAS CITY, MISSOURI.

ADJUSTABLE BEDCOVER FASTENER.

Application filed August 14, 1922. Serial No. 581,657.

To all whom it may concern:

Be it known that I, JULIUS A. PETZOLD, a citizen of the United States, residing at Kansas City, in the county of Jackson and State of Missouri, have invented a certain new and useful Improvement in Adjustable Bedcover Fasteners, of which the following is a complete specification.

This invention relates to bed clothes holders, and more especially to devices for use primarily on beds or cribs for very young children or infants and on invalid beds, where it is desirable to so support the bed covering that it shall be available to keep the occupant of the bed warm by snugness of fitting, or leave such occupant perfect freedom of movement and free from the weight of the covers while affording protection by the latter from drafts.

20 A further object is to provide an attachment susceptible when fitted snugly for the warmth of the bed occupant, of holding the covers spaced to accommodate his turning movements so that the occupant may turn 25 or roll without restraint and yet be kept snugly covered at all times and at the same time be prevented from getting upon the covering for the protection thereof.

With these general objects in view the invention consists in certain novel and useful features of construction and combinations of parts as hereinafter described and claimed; and in order that it may be fully understood reference is to be had to the accompanying drawing in which:—

Figure 1 is a perspective view of a bed equipped with a cover fastening and supporting attachment embodying the invention.

Figure 2 is an enlarged section of the same taken at the inner side of the posts, the attachment being shown in lowered position with the cover omitted.

Figure 3 is an enlarged transverse section taken on the line III—III of Figure 2, but with the cover shown in operative position.

Figure 4 is a detailed perspective view showing one of the footrail supports of the attachment.

Figure 5 is an enlarged section taken on the line V—V of Figure 2.

Referring to the drawing in detail, 1 indicates a bed of any suitable or preferred type and 2 the mattress thereof. 3 indicates the side rails of the bed which are preferably

of such character and so supported as to provide spaces 4 at their extremities, as shown clearly by Figure 2.

Referring now to the attachment for supporting the bed cover C, 5 indicates a pair of substantially S shaped springs resting upon the side rails of the bed at the foot end thereof and equipped with inverted U-shaped extensions 6 for fitting over the footrail and between the latter and the side rails 3 in the spaces 4, screws or the like, not shown, being employed to fasten said support firmly in place.

Formed integrally with the resilient supports 5, are longitudinally-extending spring clamps 7 of convolute form in cross section. Said spring clamps are of any suitable length but usually will extend from the support 5 to about the position occupied by a pillow, not shown. The front ends of the spring clamps are suitably secured to collapsible or folding supports 8, composed of a plurality of sections pivoted together in a manner similar to the sections of a two-foot rule, the undermost sections indicated at 9, resting upon the side rails and terminating in inverted U-shaped portions 10 fitting over the head rail of the bed and between said head rail and the side rails within the spaces 4, said sections 9 being secured rigidly in place in any suitable manner as explained with reference to the supports 5. The foldable supports 8 are of such proportion by preference that when fully extended their upper ends shall occupy a higher plane than the upper ends of the supports 5, so that the spring clamps under such conditions, shall slope downwardly towards the foot end of the bed as shown clearly by Figure 1, it being also preferable that said supports 8, when extended as shown by Figure 1, shall be locked in such position so as to be incapable of collapse or folding movement under the weight sustained by the supports.

A pair of rods 11 are suspended as at 12 from the spring clamps, and when in such position the cover C is stretched across the bed and between said rods and the spring clamps, and to secure or fasten the cover in place, the rods are then raised and slipped or fitted into the convolute spring clamps and carry the interposed portions of the cover with them, it being noted that the mouths or outer ends of the convolute cham-

bers of the spring clamps, face outwardly so that when the cover is secured in place as explained, any lateral pull thereon by the cover will tend to retain the rods in the said 5 clamps and the cover firmly in place. In this connection it may be stated that the width of the mouth of each clamp may be such as to require some force to be exerted on the rods and cover to force the same into 10 place, the inner ends of the clamps or the outer ends thereof yielding slightly to permit said parts to be secured in such operative position. It will be understood however, that the convolute parts termed spring 15 clamps, need not be of spring material, as their convolute form will, in conjunction with the respective rods, serve as efficient fasteners for the sides of the bed cover.

With the parts in position as explained, it 20 is obvious that a child lying upon the mattress below the cover and kicking or pushing upward upon the latter when the supports 8 are in folded or collapsed position as shown by Figure 2, will simply cause the 25 partial unfolding of said supports 8, and that the latter will again collapse when the upward pressure is removed so as to return the cover to its lowered or normal position and thus cause it to engage the child with 30 sufficient snugness to keep him warm without interfering in any way with his rolling or turning movements.

If it is desired to protect the child or occupant of the bed from drafts without 35 covering him snugly, the attendant will adjust the supports 8 to position shown by Figure 1, and thereby raise the cover to such position that it will not contact with or confine the child in any manner. It is obvious 40 that whether the cover is permitted to occupy a depressed position as shown by Figure 2, or an elevated position as shown by Figure 1, it will be impossible for it to be so disarranged as to permit the occupant of 45 the bed to rest upon it. It will therefore be kept in a clean and sanitary condition and

always present a smooth and neat appearance.

From the above description it will be apparent that I have produced an attachment 50 embodying the features of advantage set forth as desirable in the statement of the object of the invention and which obviously may be modified in various particulars without departing from the principle of construction and mode of operation involved. 55

It will also be apparent that the invention is susceptible of quick and easy attachment to practically any type of bed or that it may form an integral part of the said bed itself, 60 and it will likewise be apparent that the device is of simple, strong, durable and inexpensive construction.

I claim:—

1. In a bed clothes holder, a fastening 65 means for the covering at opposite sides of a bed, and means supporting the fastening means yieldingly as regards up and down movement of the latter; the means supporting the foot ends of the fastening means 70 tending to hold the latter yieldingly depressed and the means supporting the head ends of the fastening means being extensible to a locked position to prevent accidental lowering of such ends of the fastening means 75 under the gravitational force of the latter.

2. In a bed clothes holder, a support and fastening means for the cover comprising a pair of longitudinally extending cover-engaging means, means supporting the foot 80 ends of said cover-engaging means and permitting the same to swing in a vertical plane, and means supporting the head end of said cover engaging means, comprising a pair of supports composed of a plurality of 85 sections hingedly connected together and attached at their lower ends to the bed frame and at their upper ends to the said cover-supporting means.

In witness whereof I hereunto affix my 90 signature.

JULIUS A. PETZOLD.
